UNITED STATES PATENT OFFICE.

FREDERICK W. KLINCK, OF ALBANY, NEW YORK.

FIRE-ESCAPE.

SPECIFICATION forming part of Letters Patent No. 636,264, dated November 7, 1899.

Application filed June 1, 1899. Serial No. 718,974. (No model.)

To all whom it may concern:

Be it known that I, FREDERICK W. KLINCK, of the city and county of Albany, State of New York, have invented new and useful Improvements in Fire-Escapes, of which the following is a specification.

My invention relates to fire-escapes, and more particularly to certain improvements thereon whereby an endless ladder is formed 10 by rungs inserted between two endless sprocket-chains, with the latter producing the sides of the ladder, arranged to depend from and each arranged to run with and upon one of two sprocket-wheels keyed onto the 15 same shaft, with the latter having a pinion keyed thereon which by means of an intermediately-located gear-wheel is caused to mesh into a pinion mounted upon a shaft having keyed thereon an escapement-wheel 20 controlled by a pawl and detent arranged upon a rock-shaft that is provided with a weighted arm, whereby when tension is produced upon that one of the depending stretches of the endless ladder not held by 25 the detent such depending ladder stretch will be operated to descend, with alternating periods of movement and rest, and the other stretch of the ladder operated to rise.

My invention also relates to a trolley connection with a track attached to the front of the house or building to which my improved fire-escape is to be attached, whereby the mechanism operating the ladder may be moved along the front of the house to which 35 it is applied, so as to operate from different points thereon.

Accompanying this specification to form a part of it there are three plates of drawings containing six figures illustrating the application of my invention, with the same designation of parts by letter reference used in all of them.

Of the illustrations, Figure 1 is a front elevation of the ladder and the frame inclosing the mechanism by which the ladder is operated and shown as connected to a trolley-track arranged on the front of the building. Fig. 2 is a side elevation of the parts shown at Fig. 1, but with the track for the trolley connection shown in cross-section. Fig. 3 is a top view of the mechanism by which the ladder is operated, with the ladder omitted and the frame in which the operating mech-

anism is contained shown in transverse section. Fig. 4 is a section taken on the line x^2 55 x^2 of Fig. 3. Fig. 5 is a section taken on the line $x' x'$ of Fig. 4; and Fig. 6 is an enlarged front view of the apparatus, showing also parts of the ladder sides.

The several parts of the apparatus thus 60 illustrated are designated by letter reference, and the functions of the parts are described as follows:

The letter F designates the frame producing the inclosure H, having the rounded top 65 M, in which inclosure the ladder-operating parts are mounted. The letters B designate brackets which are outwardly projected from the building A, to which my improved fire-escape is shown as applied. The letter T 70 designates a track connected to the under side of the brackets B and depending therefrom. The letters W W designate wheels each having the flange f^2 and a tread t^2 , with each pair of said wheels mounted to journal 75 in an arm a^2 , of which there are two upwardly projected from the top M of the frame F, and each pair of said wheels W is adapted to make a trolley engagement with the track part t^3 of the track T, as shown at Fig. 4. As thus 80 constructed the mechanism in the mounted frame part F can be moved along the front of the building to be operated from any desirable point.

The letter S' designates a shaft having 85 mounted thereon the sprocket-wheels $S^2 S^2$, which are preferably made integrally with the sleeve I at each end of the latter, with the sleeve mounted upon and secured to the shaft S', with the latter having journals at J, in the 90 front and rear wall of the frame F, in which to turn. The perimeter of each of these sprocket-wheels S^2 , as indicated at p, is shown to be grooved at g' and where thus grooved to be recessed at regular intervals to produce 95 the sprocket-sinks m^2 , which receive the links of the chain C, forming the ladder sides G G, to actuate them.

The letter P designates a pinion that is mounted upon the shaft S' at one of its ends, 100 outside of the sleeve I, so to be moved with and by said shaft when the sprocket-wheels mounted thereon are being actuated by the ladder K.

The letter D designates a shaft that is provided with bearings at d^2 , in the front and

rear walls of the frame F, in which to journal, and the letter D² designates a gear-wheel mounted upon said shaft D and arranged to mesh into the pinion P upon the shaft S' and to be turned with the shaft D. The letter L designates another shaft, which is provided with bearings at l², in the front and rear of the frame F, in which to journal, and the letter P³ designates a pinion which is mounted upon said shaft L, so as to turn with it and to mesh into the gear-wheel D² upon the shaft D. The letter E designates an escapement-wheel which is also mounted upon the shaft L, so as to be turned by it.

15 The letter R designates a rock-shaft having journals at r², in the front and rear of the frame F, in which to be reciprocatingly rotated. The letter U designates a pawl which is rigidly attached to said rock-shaft, and d⁴ 20 a detent which is also rigidly attached to said rock-shaft R. The letter O designates a crank-arm which is outwardly projected from said rock-shaft and at its outer end is provided with the weights W³.

25 The letter h² designates a stop against which the arm O rests in its descent after having been raised by the engagement of one of the teeth of the escapement-wheel with the pawl U.

30 The letters N designate the rungs of the ladder, which at their ends connect with the chain C, forming the ladder sides G G.

The operation of the apparatus thus described is as follows: The ladder-chain having been housed in an upper room of the house, when a fire occurs in the latter and it becomes necessary to use the apparatus the ladder, with its sides G G each over one of the sprocket-wheels S², is allowed to descend, 35 so as to be in the position shown at Figs. 1 and 2. While thus placed, one of the depending stretches of the ladder and that designated at V' will be rigidly held upon the sprocket-wheels by the connection that the 40 detent d⁴ makes with the escapement-wheel E and the geared connection which the shaft of the latter makes with the sprocket-wheel shaft S'. As thus rigidly held, the stretch V' 45 may be used as a ladder for the ascent of a fireman or others who desire to aid in the descent of occupants. When persons are placed upon the rungs of that stretch of the ladder designated at V², they will cause that stretch of the ladder to slowly descend until they 50 reach the ground automatically and without stepping from rung to rung and the other stretch V' of the ladder caused to rise. Thus children or infirm persons may be strapped to the rungs of the descending ladder stretch 55 60 and safely deposited upon the ground.

In my improved fire-escape the endless ladder K depends from the sprocket-wheels, by which its movements are regulated, and without any other support or connection in the 65 way of another sprocket-wheel having bearings in a frame at the lower end of the ladder, and in this respect it differs from older de-

vices in which a sprocket-wheel is employed at the upper as well as the lower stretches of the ladder, with that one of the sprocket-wheels which is at the lower end of the ladder journaled in a frame. Another difference is manifested, when a ladder constructed and arranged to be operated according to my invention is compared with older constructions for the same purpose, in the fact that my endless ladder is not encumbered with cages or seats and can be operated continuously without having its descending loaded stretch raised before it can repeat the descent.

There are other important uses to which my invention may be applied in case of fire in the building upon which the apparatus is placed. Thus hose may be connected to the 85 depending stretch V', and by pulling upon the other stretch the hose and men to handle it may be raised to any window of the building where it is desired to use the hose. Being movable on the track T, the apparatus 90 may be moved along the building front, so as to escape the action of fire and flame coming from some of the windows, thus giving it a great advantage over stationary fire-escapes. The ladder chains and rungs are made of 95 metal, and the mechanism operating the latter is so housed in as to be protected from the action of the weather.

Having thus described my invention, what I claim, and desire to secure by Letters Patent, is—

1. In a fire-escape, an endless-chain ladder and sprocket-wheels whereby it is suspended in combination with an escapement and intermediate gearing, a depending trolley-track 105 and a casing in which the said sprocket-wheels, escapement and gearing are journaled and which incloses them except on the under side, the said casing being provided with rigid upward arms bearing rotary trolleys which are adapted to run on the said track, substantially as set forth.

2. The combination with the endless ladder K, having the sprocket-chain sides G, G, and intermediately-placed rungs N, of the shaft S', having the sprocket-wheels S², S², and the pinion P, mounted thereon; the shaft D, having the gear-wheel D², mounted thereon and arranged to mesh into the pinion P; the shaft L, having mounted thereon the escapement-wheel E, and pinion P³; and the rock-shaft R, provided with the pawl U, and the detent d⁴, and the weighted arm O, constructed and arranged to be operated substantially as and for the purposes set forth.

Signed at the city of Troy, New York, this 21st day of April, 1899, and in the presence of the two witnesses whose names are hereto written.

FREDERICK W. KLINCK.
